(57) **CLAIM**

The ornamental design for a cabinet, as shown and described.

DESCRIPTION

FIG. 1 is a perspective view of the cabinet showing the new design, the two lateral side views being mirror images of each other,

FIG. 2 is a front view thereof,

FIG. 3 is a side view thereof,

FIG. 4 is a rear view thereof; and,

FIG. 5 is a bottom view thereof.

The broken line showing of feet, hardware and louvered panels is for illustrative purposes only and forms no part of the claimed design.

1 Claim, 3 Drawing Sheets
